Primary Examiner — Mimosa De(74) *Attorney, Agent, or Firm* — John P. Zimmer; Smith Moore Leatherwood LLP(57) **CLAIM**

The ornamental design for a seat, as shown and described.

DESCRIPTION

FIG. 1 is a perspective view of a seat showing our new design;
 FIG. 2 is a rear end view thereof;

FIG. 3 is a front end view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dashed broken lines shown in the drawing figures are for illustrative purposes only and form no part of the claimed design.

1 Claim, 7 Drawing Sheets(56)
